UNITED STATES PATENT OFFICE.

ORA A. COLBY, OF IRWIN, PENNSYLVANIA, ASSIGNOR TO WESTINGHOUSE ELECTRIC
& MANUFACTURING COMPANY, A CORPORATION OF PENNSYLVANIA.

RADIANT HEATER UNIT.

Application filed May 12, 1923. Serial No. 638,488.

To all whom it may concern:

Be it known that I, ORA A. COLBY, a citizen of the United States, and a resident of Irwin, in the county of Westmoreland and State of Pennsylvania, have invented a new and useful Improvement in Radiant Heater Units, of which the following is a specification.

My invention relates to electrical heating devices and particularly to electric air heaters.

One object of my invention is to provide a relatively simple, compact electric air heater that may be easily assembled and disassembled.

Another object of my invention is to provide an electric air heater comprising a plurality of independent heating units.

Another object of my invention is to provide an electric air heater comprising a plurality of vertical skeleton frames for supporting a plurality of radiant heating elements.

In practicing my invention, I provide a casing having an opening in the front portion thereof and locate in said casing back of said opening, a reflector plate of refractory material. I provide a plurality of vertically extending skeleton frames, of refractory electric-insulating material, located in adjacent relation relatively to each other in the casing in front of said reflector plate and mount in each frame a helically-wound resistor member.

I provide means for supporting the skeleton frames and a suitable control switch located outside of the casing.

In the single sheet of drawings,

Figure 1 is a view, in front elevation, of an electric air heater embodying my invention,

Fig. 2 is a view, in vertical lateral section therethrough, taken on the line II-II of Fig. 1,

Fig. 3 is a view, in front elevation, of a skeleton frame embodying my invention,

Fig. 4 is a view, in side elevation, of the member illustrated in Fig. 3,

Fig. 5 is a bottom view of the member illustrated in Figs. 3 and 4, and

Fig. 6 is a partial view of a modified form of terminal construction for a skeleton frame embodying my invention.

An electric air heater 11 comprises a casing 12 that may be of any suitable or de-

sired contour and dimensions and is here illustrated as being substantially rectangular in outline. The casing 12 may comprise any suitable or desired construction embodying metal sides, back and bottom members 60 located on a supporting structure 13 that is provided with suitable supporting members 14. A top member 15 is provided and is of such form as to harmonize with the other parts of the casing and of the supporting 65 structure to provide an electrical heater casing of pleasing form and outline.

A front portion 16 of the casing is provided with a depressed part 17 and an opening 18 therein. A protecting skeleton frame 70 or grating 19 is located in front of the opening 18 and it comprises a plurality of laterally and of longitudinally extending wires or bars suitably secured together. The vertically extending bars may fit loosely into 75 suitable openings 21 at the top part of the depressed portion 17 and the bottom ends of these bars may fit loosely into the openings 22 in the bottom part of the depressed portion 17 to hold the grate 19 in its proper 80 operative position in front of the opening 18.

A horizontally extending bar 23 is secured to the vertically extending bars to limit the downward movement of the grating in the openings 21 and 22, it being understood that 85 the upper ends of the vertically extending bars are first placed in the openings 21 and the assembled grating then moved into position by a lateral and a tilting movement thereof.

A reflector plate 24, of suitable refractory material, is located within the casing back of the opening 18 and is supported by a horizontally extending bar 25 of a suitable refractory electric-insulating material that 95 is supported in the casing in substantially the position illustrated in Fig. 2 of the drawing by any suitable or desired means (not shown).

A plurality of refractory skeleton frames 26, of electric-insulating material, are located in closely adjacent or in spaced relation, relatively to each other, in the casing in front of the plate 24 and back of the opening 18 and they have their lower ends 100 extending into, and fitting within, spaced openings 27 provided in the upper surface of the member 25. Each of the members 26 comprises a frame of substantially H-section, the central web thereof extending 110

angularly relatively to the side flanges thereof, so that the rear part of the two spaced flanges is shallower at the top end than at the bottom end, as may be noted particularly by reference to Fig. 4 of the drawing. A plurality of bridges 28, of arcuate form, extend in spaced pairs from the side flanges to lugs 29 located intermediate the side flanges on the front of the central web of the members 26, substantially as illustrated in Fig. 3 of the drawing.

Openings 31 are provided beneath those ends of the bridges 28 connecting the same to the side flanges, to permit of the easy manufacture of the skeleton frames. An integral bottom portion 32 is provided for each of the skeleton frames 26 and a flattened top portion 33 is provided to permit of holding the upper end of the respective frames 26 in their proper operative positions within the casing 12, a bar 34 being provided within the casing 12, the rear surface of which may be engaged by the front surface of the portions 33, substantially as illustrated in Fig. 2 of the drawing.

A radiant heating element is provided for each of the skeleton frames 26 and it comprises a helically wound resistor member 35 that is located in the skeleton frame in operative engagement with the front surface of the central web and also in operative engagement with the inner face of the side flanges thereof, substantially as illustrated in Fig. 1 of the drawing. The resistor member 35 is, therefore, located underneath the bridges 28 of arcuate form and it extends from the bottom of the frame to the top portion on the one side of the integral lugs 29, and then back down to the bottom of the frame on the other side of the lugs 29, whereby a substantially imbedded resistor is obtained that is protected against accidental contact with an adjacent resistor by integral portions of the co-operating enclosing skeleton frame. The ends of the resistor members 35 extending backwardly through suitable openings 36 in the central web and then through suitable vertical openings 37 in the bottom portion 32.

A means for permitting the selective energization of the heating units constituted by the respective skeleton frames 26 and by the resistor member 35 respectively associated therewith, may comprise a pair of bus bars 38 that are located in proper operative spaced relation relatively to each other, by being suitably secured against blocks 39, of refractory electric insulating material, at the ends thereof. The distance between the outer surfaces of the blocks 39 is such as to permit the structure being located within the casing 12, substantially as illustrated in Fig. 1 of the drawing.

An opening 41 is provided in one of the side portions of the casing 12, through

which the structure comprising the two bus bars 38 and the two blocks 39 may be inserted and removed, as required. A block 42 of a suitable refractory electric-insulating material may also be suitably secured against one of the blocks 39 and may be of such dimensions as to cover the opening 41 and be secured against the side of the casing by a plurality of screws 43. A control switch 44 may be mounted on the outside of the block 42 and may be of any suitable or desired type to permit of selective energization of the heating elements hereinbefore described.

The ends of the resistor member 35 are suitably secured to the bus bars 38 by machine screws 45. Terminal pins 46 are provided on the block 42 to permit of connecting thereto the ends of a suitable supply circuit conductor, (not shown) in any manner usually employed in the art.

Should it become necessary to renew the resistor member 35 in any one or all of the skeleton frames 26, the ends of the resistor members may be disconnected from the bus bars 38 by suitable tools, an opening 47 being provided in the rear part of the casing to permit of access thereto.

Fig. 6 illustrates a modified form of terminal construction for the individual heating units. Suitable terminal members 48 of bar form and of different lengths, are secured to the bottom portion 32 of the skeleton frames 26, as by screws 49 and these terminal members are of such length that they can be directly connected to the bus bars 38 in case it is considered necessary or desirable, to provide such relatively heavy terminal members. The openings 27 are, of course, modified to permit of properly receiving the ends 32 and the bar terminals, the latter projecting through the support 25.

The device embodying my invention thus provides a plurality of skeleton frames supporting a resistor member that becomes incandescent when traversed by a normal current and thus simulates the operation and looks of the usual gas heated radiant stove. The individual heating elements may be quickly inserted in or quickly removed from the casing, relatively few operations only being necessary to effect such changes.

Various changes in detail and arrangement may be made without departing from the spirit and scope of the invention, and such modifications are intended to be covered by the appended claims.

I claim as my invention:

1. In an electric heater, in combination, an elongated, refractory, resistor-supporting member comprising a skeleton frame of substantially H-section, and integral, spaced members on one side of said frame intermediate the side flanges thereof, and a re-

sistor member extending between said flanges and said intermediate members.

2. In an electric heater, in combination, an elongated, refractory, resistor-supporting member comprising a skeleton frame of substantially H-shape in lateral section, integral spaced lugs on one side of said frame intermediate the side flanges thereof and bridges, of arcuate form connecting said lugs and the side flanges at spaced points, and a helical resistor member extending between said flanges and said intermediate lugs and under said bridges.

3. In an electric heater, in combination, an elongated refractory, resistor-supporting member comprising a skeleton frame of substantially H-shaped in lateral section, a plurality of integral, spaced, lugs on one side of said frame extending longitudinally intermediate the side flanges thereof, and bridges of arcuate form extending in pairs from said lugs to the side flanges at points intermediate said lugs, and a resistor mem-

ber extending between said flanges and said lugs and under said bridges.

4. In an electric heater, in combination, an elongated refractory, resistor-supporting member comprising a skeleton frame of substantially H-shape in lateral section, a plurality of integral, spaced, lugs on one side of said frame extending longitudinally intermediate the side flanges thereof, bridges of arcuate form extending in pairs from said lugs to the side flanges at points intermediate said lugs, and a contact-terminal-supporting member at the lower end of said skeleton frame, a resistor member extending between said flanges and said lugs and under said bridges, and contact terminals secured to said contact-terminal-supporting member.

In testimony whereof, I have hereunto subscribed my name this 7th day of May 1928.

ORA A. COLBY.
